Primary Examiner — Marcus Jackson(74) *Attorney, Agent, or Firm* — Lerner, David, Littenberg, Krumholz & Mentlik, LLP(57) **CLAIM**

The ornamental design for an autonomous vehicle taillamp, as shown and described.

DESCRIPTION

FIG. 1 is a front perspective view of an autonomous vehicle taillamp according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

The embodiment illustrates the autonomous vehicle taillamp arranged for use on a first side of a vehicle. Another embodiment encompassed by this design include the autonomous vehicle taillamp on an opposite side of the vehicle, wherein such embodiment is a mirror image of the first side. Broken lines are environmental only and form no part of the claimed design.
